TRAFFIC DIRECTING SYSTEM FOR PARKING AREAS

Richard R. Smith, Rochester, N.Y., assignor to General
Signal Corporation

Filed May 1, 1961, Ser. No. 106,918

4 Claims. (Cl. 340—51)

This invention relates to a traffic directing system for parking areas, and, more particularly, relates to such a system for directing vehicles with respect to a parking area and with a cautioning signal being employed for apprising vehicle operators of the space condition in such area.

In modern parking areas and garages, it is considered desirable to provide a counting system which registers the number of vehicles entering and exiting from a parking area so as to provide a running count of the number of available spaces within such area. Such a system is normally employed to control an indication means provided for directing vehicles into the area or away from such area.

The convenience of having such counting system to control the indication means mentioned above has been recognized by the prior art to the extent that such an indication means is controlled for directing vehicles into the area until such area is completely filled. When such area is filled to capacity, remaining vehicles are directed away from the parking area. It is also recognized that a predetermined number of vehicles be permitted to leave a parking area which has been filled to capacity before the detection means is once again controlled to direct vehicles into such area.

It is proposed in this invention to provide a system controlled by the counting system of a parking area for directing vehicles into or away from a parking area. This invention also provides for apprising the operators of vehicles that a given parking area is near capacity but has not been completely filled to capacity. It is further proposed in this invention to provide for cautioning vehicle operators being directed away from a parking area that such area has at least one available space.

Thus, one object of this invention is to provide a system for apprising vehicle operators of the nearly filled condition of a given parking area.

Another object of this invention is to provide a system for apprising vehicle operators of the soon-to-be-available parking spaces.

Other objects, purposes and characteristic features of the present invention will be in part obvious from the accompanying drawings, and in part pointed out as the description of the invention progresses.

The drawing illustrates one embodiment of this invention.

Referring to the drawing, a differentially controllable counter DC, which indicates the number of available parking spaces, is shown as having an add coil and a subtract coil. In this type of counter, both the add coil and subtract coil need only to be pulsed briefly to cause the counter to either add or subtract a count. The add coil is shown to be pulsed by the actuation of a button 10, while the subtract coil is shown to be pulsed by the actuation of a button 11. Additionally, the add coil and subtract coil of counter DC may be controlled by an automatic control AC which can be a counting system, as briefly mentioned above.

The counter DC includes a units decade UD and a tens decade TD each of which has a read-out control switch, such as switches RO1 and RO2 which are respectively controlled to positions representative of the count registered upon the corresponding decade UD or TD.

2

Signalling means 12 includes two arrows 16 and 17 and a circular indication 18. Arrow 16 when illuminated directs vehicles into the area, and arrow 17 when illuminated directs vehicles away from the area. The circular indication 18 provides a caution indication in conjunction with either arrow 16 or 17. Arrows 16 and 17 may be colored green, while circular indication 18 may be colored yellow, or as otherwise desirable. Moreover, it is considered as being within the scope of this invention to utilize the arrows 16 and 17 and circular indication 18 either in combination or separately for indicating the capacity conditions of a parking area to a responsible person such as the parking area attendant.

Relay FR controls through its contact 20 the illumination of arrows 16 and 17. When relay FR is dropped away arrow 16 is illuminated, but when relay FR is picked up arrow 17 is illuminated instead. Relay FR can only pick up when the count registered by counter DC is 00 since only then will relay T0 be energized through contact 23 of decade switch RO2 and relay U0 through contact 25 of decade switch RO1 thereby completing a circuit for the energization of the wiring of relay FR through the respective closed contacts 26 and 38 of these two relays T0 and U0. Once relay FR is picked up, a stick circuit is completed to maintain it energized through back contact 42 of relay U5 and front contact 43 of relay FR. Because of this, relay FR will remain picked up until there are five or more parking spaces again available since it is only when this condition is met that the stick circuit for this relay can be interrupted. Incidentally, if the number of vehicles entering the parking area should exceed its capacity so that counter DC will be operated beyond the 00 condition such as by being operated to the 99 condition, then relay FR will still remain picked up because then an alternate stick circuit will be completed through back contact 48 of relay T0 and through front contact 43 of relay FR.

Before the parking area is filled to capacity so that relay FR is picked up, relay NFR is picked up. Thus, when the count registered upon counter DC is 04 so that relays T0 and U4 are energized, a circuit is completed to energize relay NFR through the closed contacts 26 and 27 of the relays T0 and U4 respectively. As the count thereafter is decreased below 04, relay NFR is continually energized since a stick circuit will be established for this relay through back contact 33 of relay U0, back contact 34 of relay U5, and front contact 36 of relay NFR. This stick circuit will be maintained until the count reaches 00 at which time relay U0 will pick up and interrupt the circuit by the opening of back contact 33.

To summarize the operation thus far, relay FR remains dropped away as the count decreases toward 0 and is picked up only when the count actually reaches 00 upon counter DC. Until this happens, arrow 16 is illuminated so as to direct incoming vehicles into the corresponding parking area, but when the count of 00 is reached, relay FR picks up and arrow 17 is then illuminated while arrow 16 is extinguished. Subsequent vehicles are then directed to an alternate parking area. However, from the time that the count on counter DC reaches 04 and until it reaches 00, relay NFR is picked up so that the circular indication 18 is illuminated and this indicates to arriving motorists that, although they are being directed by the illuminated arrow 16 into the respective parking area, there are only a few parking spaces still available in that area. Of course, when the capacity of the parking area has been reached so that arrow 16 is no longer illuminated, then it is no longer desired to illuminate the circular indication 18 and it is for this reason that relay NFR is controlled to drop away when the count reaches 00 on counter DC.

When vehicles begin to exit from the assuming parking

area, relay NFR is once again controlled to a picked up condition for illuminating circular indication 18 and is maintained in such picked up condition until the read-out control switch RO1 is effective to pick up a relay U5. More specifically, when the count registered upon counter DC ascends as additional parking spaces become available, relay NFR is again picked up. In the drawing, this is shown to occur when the count reaches 01. At that time, an alternate pick-up circuit for relay NFR is established through back contact 33 of relay U9, back contact 34 of relay U5, front contact 45 of relay U1, front contact 46 of relay T9, to the winding of relay NFR. Upon the picking up of relay NFR the previously-described stick circuit is again completed, and since this stick circuit includes back contact 34 of relay U5, the stick circuit will be interrupted when the count of 05 is reached. In other words, as increasing numbers of parking spaces become available, relay NFR which is picked up at the time the first such parking space becomes available, remains picked up until there are five such available spaces. Throughout this time, the circular indication 18 is steadily illuminated. As previously mentioned, the stick circuit which has been maintaining relay FR energized includes back contact 42 of relay U5 and this means that relay FR is also continually energized during this time that additional parking spaces are becoming available, and this condition continues to prevail until five parking spaces have been available so that relay U5 picks up. Throughout this time, therefore, arrow 17 has been steadily illuminated so that incoming traffic has been diverted to an alternate parking area. Concurrently, circular indication 18 has been illuminated to inform the incoming motorists that, although they are being directed to an alternate area, one or more spaces are now available in the parking area governed by signalling means 12 and that traffic may soon again be directed into that area.

It is apparent from the drawing that the relays U4 and U5 could have their respective pick up circuits completed through other contacts of switch RO1 so as to vary the illumination control of the arrows 16 and 17 with respect to circular indication 18 to provide the above-mentioned caution indications.

Having described a traffic directing system for parking areas, as one specific embodiment of the present invention, it is desired to be understood that this form is selected to facilitate in the disclosure of the invention rather than to limit the number of forms which it may assume; and, it is to be further understood that various modifications, adaptations and alterations may be applied to the specific form shown to meet the requirements of practice, without in any manner departing from the spirit or scope of the present invention.

What I claim is:

1. In a parking facility having at least two parking areas, means for registering at each instant the number of available parking spaces in the first of said areas, signalling means being operable to present a first signal indication directing further incoming vehicles into said first area and to present alternatively a second signal indication directing further incoming vehicles to the second of said areas, means coupled between said registering means and said signalling means for controlling said signalling means to display said first signal indication so long as the number of available parking spaces registered by said registering means exceeds a predetermined number and to display said second signal indication when the number of available parking spaces registered by said registering means fails to exceed said predetermined minimum number, auxiliary signal indication means also controlled by said coupling means and being operable to display a distinctive signal indication for all count values registered by said registering means exceeding said pre-

terminated minimum value but not exceeding a predetermined higher value, whereby said first signal indication is displayed by said signalling means and incoming vehicles are directed by said signalling means to said first parking area until said predetermined minimum value is registered by said registering means but said auxiliary indication is displayed prior to the attainment of said predetermined minimum value concurrently with the display of said first signal indication by said signalling means to thereby indicate the imminent attainment of a filled condition of said first parking area.

2. The invention as defined in claim 1 wherein said coupling means after operating said signalling means to display said second signal indication upon the attainment of said predetermined minimum count by said registering means maintains said signalling means in a condition to thereafter display said second signal indication as the count registered by said registering means increases above said predetermined minimum value until said count registered attains a preselected second value, whereby upon a decrease in the number of available parking spaces in said first area to said predetermined minimum value results in the routing of further vehicles to said second area and vehicles are not again rerouted to said first area until the number of available parking spaces reaches said preselected value.

3. The invention as defined in claim 1 wherein said coupling means also controls said auxiliary signalling means to display said distinctive signal subsequent to the attainment of said predetermined minimum count by said registering means and for ascending values of said count until said count attains said preselected second value, whereby the concurrent display of said distinctive signal by said auxiliary signal indication means with the display of said second signal indication by said signalling means indicates to incoming motorists the probability imminent routing of further vehicles to said first parking area by said signalling means.

4. In a parking facility having at least two parking areas, first means for counting each vehicle entering the first of said areas, second means for counting each vehicle leaving said first area, differential counting means governed jointly by said first and second counting means for registering the number of available parking spaces in said first area, signalling means governed by said differential counting means to display a first signal indication directing vehicles into said first area when the count registered by said differential counting means exceeds a predetermined minimum value and to display a second signal indication directing vehicles away from said first area and to said second area when the count registered by said differential counting means does not exceed said predetermined minimum value, and auxiliary signal indication means being selectively operable to display a distinctive signalling indication concurrently with the display of said first or second signal indication by said signalling means for predetermined count values registered by said differential counting means which exceed said predetermined minimum value, whereby the display of said distinctive signal indication concurrently with the display of said first signal indication warns incoming vehicles of the imminent routing of vehicles to said second area and the concurrent display of said distinctive indication with said second signal indication warns incoming vehicles of the imminent routing of further vehicles back to said first area.
